ORNAMENT

Jack Salzman, Bronx, N. Y.

Application February 25, 1935, Serial No. 8,109

4 Claims. (Cl. 40—140)

This invention relates to ornaments and has special reference to ornaments having parts adapted to be assembled with a main part.

One important object of the invention is to provide a novel structure for ornaments having a main or base part and separate parts carrying initials or other ornamental features, said separate parts or inserts being adapted for selective assembly with the base.

10 A second important object of the invention is to provide a device of this character wherein a rigid base and separate parts or inserts have co-acting means enabling the separate parts to be correctly positioned in the base.

15 A third important object of the invention is to provide separate parts or inserts for such ornaments having bendable prongs adapted to lie behind the base, the latter being so formed that the prongs, when bent to secure the separate parts 20 or inserts in position, will lie flush with the rear face of said base.

With the above and other objects in view as will be presently understood, the invention consists in general of certain novel details of construction and combinations of parts hereinafter 25 fully described, illustrated in the accompanying drawing and specifically claimed.

In the accompanying drawing, which is drawn to a magnified scale, like characters of reference 30 indicate like parts in the several views, and:—

Figure 1 is a face view of the ornament constructed in accordance with this invention and showing the parts assembled.

Figure 2 is a rear view thereof.

35 Figure 3 is a detail section on the line 3—3 of Figure 1.

Figure 4 is a detail section on the line 4—4 of Figure 1.

40 Figure 5 is a rear view of one of the separate parts with the prongs in the position existing before assembly.

Figure 6 is an edge view of the part shown in Figure 5.

In the embodiment of the invention disclosed 45 in the accompanying drawing there is a base member 10 having its front face preferably provided with ornamentation as at 11. In this base member there is provided one or more openings 12, the parts of the member around said openings 50 being rigid and unyieldable. Preferably these openings have each a pair of parallel sides 13. The back or rear face of this base member is preferably smooth except that along each parallel side 13 there is provided a series of shallow indentations 14, the indentations of one side

being opposite the indentations of the opposite side. Tongues 15 alternate with these indentations and project into the opening 12, these tongues being of less thickness than the material of the base and having their rear faces in the plane of the rear face of the base member. Thus the tongues project from the sides 13 in such manner as to form supports for any article placed in the opening and spanning the space between the sides 13.

10 The separate parts or inserts 16 are made in any preferred form, for instance as initials, and may have their front faces suitably ornamented. The letters of the alphabet are inserted from the front until their rear surface bears against the 15 tongues 15. Then the prongs 17 are bent into the indentations 14. These inserts are preferably somewhat thinner than the base 10 so that when an insert is placed in an opening 12 and has its back resting on the tongues 15 its face will be 20 substantially flush with the face of the base member 10. At those parts of the periphery of each insert which are intended to lie adjacent the sides 13, when the insert is in place, the insert is provided with prongs 17 which, before the insert is in place in the base, extend perpendicularly from the rear face of the insert. These prongs are so positioned on the insert that they will pass between adjacent tongues 15 and can then be bent to lie in the indentations 14. The 30 prongs preferably have a thickness corresponding to the depth of the indentations so that when bent to fit such indentations their rear faces will lie in the plane of the rear face of the base 10.

35 It will be seen from the foregoing that any desired insertion of a set such as an alphabet may be inserted in any opening 12 and there held by the tongues 15 and prongs 17. It will also be seen that, by bending up the prongs 17 of an insertion in place, such insertion may be re- 40 moved and replaced by another.

Further, it will be obvious that, while the invention is adapted for use with highly artistic ornaments, this invention is not confined to any particular type or character of ornament 45 either on the base or on the insertions. It will also be noted that the prongs 17 are so disposed as to properly center the inserts in the base.

There has thus been provided a simple and efficient device of the kind described and for 50 the purpose specified.

It is obvious that changes may be made in the form and construction of the invention without departing from the material principles involved. It is not therefore desired to confine the invention 55

to the exact form herein shown and described but it is desired to include all forms which come within the scope of the appended claims.

What is claimed, is:—

5. 1. In an ornament, a base member having an opening therein, an insert having prongs thereon adapted to be bent to lie against the back of the base member to hold the insert in place, the rear face of said base member having spaced indentations receiving said prongs when bent to hold the insert in place, and means carried by said base member and projecting into said opening, said means engaging the rear face of said insert and limiting its rearward movement through said opening.

10. 2. In an ornament, a base member having an opening therein, an insert having prongs thereon adapted to be bent to lie against the back of the base member to hold the insert in place, the rear face of said base member having spaced indentations receiving said prongs when bent to hold the insert in place, the depths of said indentations being equal to the thickness of said prongs, and means carried by said base member and projecting into said opening, said means engaging the rear face of said insert and limiting its rearward movement through said opening.

15. 3. In an ornament, a base member having an

opening therein, an insert having prongs thereon adapted to be bent to lie against the back of the base member to hold the insert in place, the rear face of said base member having spaced indentations receiving said prongs when bent to hold the insert in place, and tongues carried by the base member to project into the opening and positioned alternately with said indentations, said tongues being spaced rearwardly from the front face of the base member to support the insert in the opening and to limit its rearward movement through the opening. 5

4. In an ornament, a base member having an opening therein, an insert having prongs thereon adapted to be bent to lie against the back of the base member to hold the insert in place, the rear face of said base member having spaced indentations receiving said prongs when bent to hold the insert in place, the depths of said indentations being equal to the thickness of said prongs, and tongues carried by the base member to project into the opening and positioned alternately with said indentations, said tongues being spaced rearwardly from the front face of the base member to support the insert in the opening and to limit its rearward movement through the opening. 10 20 25

JACK SALZMAN.
